UNITED STATES PATENT OFFICE.

JAMES W. BRYCE, OF BLOOMFIELD, NEW JERSEY, ASSIGNOR TO INTERNATIONAL TIME RECORDING COMPANY, OF ENDICOTT, NEW YORK, A CORPORATION OF NEW YORK.

TIME RECORDER.

Application filed August 17, 1922. Serial No. 582,346.

To all whom it may concern:

Be it known that I, JAMES W. BRYCE, a citizen of the United States of America, residing at Bloomfield, in the county of Essex and State of New Jersey, have invented certain new and useful Improvements in Time Recorders, of which the following is a full, clear, and exact description.

In time recorders it is customary to make the device which supports the record sheet movable in two directions, usually laterally and vertically, to permit various spaces on the sheet being brought to the printing position.

Such movements are usually controlled directly by the clock but are in part effected by manual operations which effect a shift of the card position relatively to the type upon a change of a day, or upon change of in or out registrations which are made upon the same day.

The present invention is directed to the provision of improved devices for effecting the shifting of the card receiver by a manual operation to an extent determined by a clock controlled element. While in the embodiment herein illustrated the shifting devices are utilized for in and out spacing, it will be understood that by the provision of a proper form of card such devices may be used for day to day shifting operations.

Referring to the drawings,

Fig. 1 is a front view of the machine with the casing removed.

Fig. 2 is a side elevational view of the machine.

Fig. 3 is a detail view showing the card receiver in displaced position.

Fig. 4 is a detail of the pawl device for displacing the time controlled cam.

Fig. 5 is a sectional view of the latching devices for the card receiver.

Fig. 6 is a view showing the irregular registration setting handle and the index therefor which is located on the outside of the casing.

In the drawings, 10 designates a card receiver open at the top and slidably mounted upon fixed guide rails 11. This receiver has its central portion open to permit the printing hammer 12 (Fig. 2) to carry the card rearward against the type ribbon 13 and the time printing type wheels (indicated by the

dotted line circle 14 in Fig. 2). The type wheels are driven from the clock train 15 in the usual and well known manner. The printing hammer 12 is impelled forward by means of a platen spring 16 (Fig. 2). The hammer is cocked by the depression of the manual operating lever 17 and at the proper time in the cycle the hammer is released to react against the card and type.

To control the relative vertical position of the card and time wheels the usual card abutment 18 is provided. This abutment is controlled in its vertical position by the time controlled cam 19. This cam is operated in the usual way from the clock driven or clock controlled time train.

Slidably mounted upon the intermediate 70 guide rail 11 is a member 20 having an up-standing abutment 21 in alignment with a pin 22 on the card receiver frame. The member 20 is interconnected to the manual 17 by means of a horizontal link 23, bell 75 crank 24 and link 25 so that upon the depression of the handle the member 20 will be slid to the right and upon the upward movement of the handle it will be moved to the left. The member 20 upon its lower 80 surface is provided with camming edges 26 and an intermediate notch 27. Member 20 also carries a horizontally extending pin 50. Pivottally mounted upon the card receiver is a pawl 28 having a shouldered portion 29 85 which is adapted to engage in the notch 27. The pawl 28 is normally resiliently rocked anti-clockwise by spring 30 so that the shouldered portion will always either tend to be in the notch or against the lower face of member 20. The pawl is further provided with a tail portion 32 which upon the contacting engagement with a stop element 33 is adapted to rock the pawl clockwise 90 from the position shown in Fig. 1 to that shown in Fig. 3.

The stop element 33 is slidably mounted in a fixed bar 34 having a plurality of notches 35 in the upper edge thereof. The stop 33 is also interconnected to a lever 36 100 by means of a pin 37 (Fig. 3).

Mounted upon the card receiver is a supplementary latching pawl 51 having a suitable notch therein to engage a shoulder on the pawl 28. The latching pawl is swung 105 anti-clockwise by a spring 52 and is released

from engagement with pawl 28 by means of the pin 50 which engages a camming slot 53 in the latching pawl at proper times to permit the swinging of pawl 28 in an anti-clockwise direction.

The lever 36 is provided with a handle which extends without the casing as shown in Fig. 2. Part 36 is pivotally mounted upon a lever 38 which is pivotally mounted 10 and provided with a follower cooperating with a time controlled cam 39. Cooperating abutments 40-41 and an interconnecting spring 42 normally tend to keep part 36 in alignment with part 38 and under the direct 15 control of cam 39, but at any time the handle may be grasped and part 36 displaced anti-clockwise thereby permitting the stop member 33 to be manually set back of a time controlled position. Normally the stop member 20 is under direct time control, i. e., under the control of cam 39. Cam 39 is mounted upon a shaft 43 which is advanced or rotated step by step by the pawl and ratchet device 44 (Fig. 4) which is in turn controlled through 25 a linkage 45 from the program wheel 46 of the clock. The program parts, being well known in time recorders, require no detailed description.

The operation of the device is as follows. 30 It will be first assumed that the time cam 39 is in the position shown in Fig. 1. The actuation of the manual 17 prior to the actual imprinting draws down link 25 and displaces the member 20 to the right. Lug 29 of pawl 28 is in engagement with notch 27 and consequently the pawl and the card receiver 10 to which it is pivoted is drawn to the right. Such movement continues until tail 32 of pawl 28 engages the stop 33 whereupon the pawl will be rocked clockwise, withdrawing lug 29 out of notch 27 and into engagement with the first shoulder on notch 35 on bar 34. The actuator member 20 is now released from the card receiver and can move forward to the limit of its travel. In moving forward the pin 50 passes out of cam slot 53 and permits the latching pawl 51 to engage pawl 28 and hold it in the position shown in Fig. 3. The card receiver then 45 positions the card at the first printing position. With the parts as shown in Fig. 1 the receiver makes practically no movement, since the stop 33 is at its extreme outward position. Fig. 3 shows a condition where the receiver has moved two steps to the right and engaged the lug 29 of pawl 28 in the third notch 35. Here the actuator 20 is shown moved to a further position. After the receiver 10 is thus positioned it is locked at 50 the printing position by pawl 28. The pawl 28 is in turn locked by latching pawl 51. The printed impression is then made upon the card in the receiver. Member 20 moves to the right to the extreme limit of its travel 55 and then returns to the left upon the return 60 and then returns to the left upon the return 65

stroke of the printing handle. Upon this movement the pin 50 engages in the cam slot 53, rocking latch pawl 51 clockwise and releasing pawl 28 so that upon the displacement of the receiver to the left caused by 70 shoulder 21 abutting pin 22, the pawl 28 may swing from the position shown in Fig. 3 to that of Fig. 1. This operation has restored all of the parts in position for a new 75 operation.

It will be seen that for each operation of the printing handle, the card receiver moves from the normal left hand home position to a time determined position where it remains during the printing operation. Thereafter 80 the receiver is returned to the home position. This operation will repeat for each operation and the card receiver will move to the same position each time until the time cam 43 changes its position. If it is desired to position the card receiver in a position other than the time cam controlled position the handle 36^a may be set to any desired position over index scale 36^b (Fig. 6). In this manner irregular registrations may be taken 85 care of.

I claim—

1. In a time recorder, in combination with a card receiver, time controlled means for determining the position of the receiver, a printing manual, means operable upon the actuation of the printing manual for displacing the receiver at each operation from a normal home position to a time determined 95 position, and means operable after each printing operation for returning the receiver to normal position.

2. In a time recorder, in combination with a card receiver, time controlled means for determining the position of the receiver, a printing manual, means for imparting a back and forth shifting movement to the receiver at each operation of the printing manual, and means for limiting the extent of one of said movements in accordance with 105 the position of the aforesaid time determined means.

3. In a time recorder in combination with a shiftable card receiver, time controlled means for determining the position thereof, an operating handle, means intermediate said handle and receiver for positively displacing the receiver at each operation of the handle, to the time determined position, means for locking the receiver in said position when printing is being effected, and means operable at each operation of the handle for thereafter unlocking the receiver and restoring it to normal position.

4. In a time recorder in combination with a card receiver, a printing handle for imprinting time imprints upon a card carried by said receiver, coupling means operable upon the depression of the printing handle for causing a displacement of the receiver 125 130

by said printing handle, time controlled means for effecting an uncoupling of the receiver and handle at a time determined position.

5. In a time recorder in combination with a card receiver, means for shifting the receiver at each operation of the machine from a normal position to a time determined position, and means for returning the receiver 10 to normal position at each operation after printing has been effected.

6. In a time recorder in combination with a card receiver, means for shifting the receiver to present different portions of a 15 card to the printing devices, said means being operable at each operation of the machine to effect such shifting movement from a normal position to a printing position and thence back to normal position, and adjust-

able controlling means for determining the 20 aforesaid printing position of said receiver.

7. The invention set forth in claim 6 in which time controlled means are provided for determining the position of said controlling means. 25

8. The invention set forth in claim 6 in which manually adjustable means are provided for determining the position of the aforesaid controlling means.

9. The invention set forth in claim 6 in 30 which the position of said controlling means is determined by time controlled means and in which manually adjustable means is provided for setting the controlling means to other positions. 35

In testimony whereof I hereto affix my signature.

JAMES W. BRYCE.
